ARCH-SUPPORTING SANDAL

Sol Stern, Brooklyn, N. Y., assignor to Kork-Ease, Inc.,
Brooklyn, N. Y., a corporation of New York

Application January 27, 1956, Serial No. 39,949

Term of patent 14 years

(Cl. D7—7)

Fig. 1 is a top plan view of the arch-supporting sandal showing my new design with holding straps attached thereto and illustrated in dotted lines;

Fig. 2 is a bottom plan view;

Fig. 3 is a side elevational view looking toward the arch-supporting portion of the sandal;

Fig. 4 is a side elevational view similar to that of Fig. 3, but seen from the opposite side thereof;

Fig. 5 is a front view of the arch-supporting sandal shown in Fig. 1; and

Fig. 6 is an enlarged perspective view of a section through the toe portion of the sandal of Fig. 1.

The characteristic feature of my design resides in the combination on the arch-supporting sandal disclosed of the marginal ledge outlining the padded upper sole of the unitary, contoured sandal as shown in full lines.

I claim:

The ornamental design for an arch-supporting sandal, substantially as shown and described.
